United States Patent Office.

DAVID EWING, OF INDIANAPOLIS, INDIANA.

Letters Patent No. 64,211, dated April 30, 1867.

IMPROVED PESSARY.

The Schedule referred to in these Letters Patent and making part of the same.

TO WHOM IT MAY CONCERN:

Be it known that I, DAVID EWING, of the city of Indianapolis, county of Marion, and State of Indiana, have invented a new and useful Improvement in Pessaries; and I do hereby declare the following to be a full and true description thereof, reference being had to the accompanying drawings, and to the letters and figures of reference marked thereon.

The nature of the invention consists in the improved construction and application of the instrument; said instrument to be made of silver, hard rubber, parkesene, or any other suitable material, of such different sizes as will suit different patients.

To enable others skilled in the art to make and use my said invention, I proceed to describe more fully as follows:

Figure No. 1 of the accompanying drawings represents a perspective view of the instrument; *a a* is a flaring rim attached to the stem *e e* by the curving arms *c c c* and *c* in such a manner that the said rim and arms together form as it were a cup or basket. Between the said arms are four open spaces represented by *d d d* and *d*. The stem is bent a little at *f*, to fit the natural curve of the vagina. At *h* are inserted into the hollow of the stem *e e* two adjustable springs represented by *g* and *g*; the whole instrument, when all the parts are in their proper places, being as represented by said fig. 1.

The instrument in used as follows: For the treatment of "*prolapsus uteri*" the end *a a* is first inserted into the vagina and pressed carefully in until the womb is raised so far that the patient is easy. The womb is then in its natural position. The distance from the interior of fleshy covering or floor of the pelvis to the uterus can in this way be accurately measured. The instrument is then taken out and the springs *g* and *g* adjusted to suit the proper length by slipping them in the hollow stem *e e* at *h*. The said springs are then fastened in the hollow of said stem by a suitable wedge. It now only remains to set the instrument in the place it is to occupy during the treatment of the patient.

A *E* and A *E* of Figure 2 of the accompanying drawings are intended to represent the two sides or walls of the vagina, joining the womb *K* at *A* and *A*, and extending to the floor of the pelvis, represented *G* and *G*. To set the pessary in its proper place, the end *a a* is inserted in the vagina as before, and pressed carefully forward until the womb assumes its natural position, great care being taken to have the mouth of the womb inside of the cup or basket *a c c a*. The springs *g* and *g*, which have been compressed up to this time, are now let go, and their elasticity carrying them apart they naturally take an easy position on the floor of the pelvis, as represented by *G g* and *g G*; of said No. 2; the said rim *a a*, resting in the annular angle formed, by the junction of the neck of the womb on the upper end of the vagina, as represented by *A a a A*, of said fig. 2. The said pessary will then be held firmly in its place, and being entirely inside of the body, will not in any way hinder the rest or locomotion of the patient. The depth of the said cup or basket *a c c a* is such that when the instrument is in its proper place, the *os uteri*, represented by *I* of said No. 2, will never touch the bottom, and so be free from any local cause of irritation. The said open spaces *d d d* and *d*, are so arranged that any discharge flowing from the womb will pass freely through them, and so find its way out of the body without any impediment. If the floor of the pelvis should become sore by any abrasion produced by the springs *g* and *g* resting on it as aforesaid, a little piece of sponge, lint, rubber, or any other such suitable material sewed or attached at the end of each of said springs, will immediately remedy the difficulty. The size of the neck *e e* is comparatively so small that it will allow the vagina, which had been disturbed by the prolapsus, to contract and reassume its natural position, when it will assist the suspensory ligaments of the womb, which will by rest and other proper treatment regain their natural tonicity, to hold it in its proper place.

What I claim, and desire to secure by Letters Patent, is—

1. The curving arms *c c c* and *c*, when constructed and combined with the rim, substantially as set forth.
2. The hollow stem *e e*, when the same is combined with the adjustable springs *g* and *g*, in manner and form as aforesaid.
3. The adjustable springs *g* and *g*, when the same are constructed and adjusted substantially as set forth and combined with the said hollow stem *e e*.
4. The improved pessary described herein, when the same is considered as a whole device, and constructed in its said several parts as aforesaid, and used in the manner and for the purpose hereinbefore described.

DAVID EWING.
